206,501

FRONT PANEL FOR AN AIR CONDITIONER UNIT

Ernest J. Prisbe, Hayward, Calif., assignor to United-Carr
Incorporated, Boston, Mass., a corporation of Delaware

Filed Oct. 23, 1965, Ser. No. 87,841

Term of patent 14 years

(Cl. D62—4)

The single figure is a front elevation of a front panel for an air conditioner unit embodying the new design, and wherein the broken lines pertain to other parts of the air conditioner unit which are included for illustrative purposes only.

This application is a continuation-in-part of application Ser. No. D.82,494 filed November 5, 1964, and now abandoned.

I claim:

The ornamental design for a front panel for an air conditioner unit, substantially as shown and described.
